UNITED STATES PATENT OFFICE

149,487

DESIGN FOR A PEA SHELLER HANDLE

Albert O. Hagen, Seattle, Wash.

Application November 18, 1946, Serial No. 134,884

Term of patent 14 years

(Cl. D89—1)

To all whom it may concern:

Be it known that I, Albert O. Hagen, a citizen of the United States of America, residing at Seattle, in the county of King and State of Washington, have invented a new, original, and ornamental Design for a Pea Sheller Handle, of which the following is a specification, reference being had to the accompanying drawing, forming a part thereof, wherein:

I claim:

The ornamental design for a pea sheller handle, as shown.

ALBERT O. HAGEN.
